UNITED STATES PATENT OFFICE.

WILLIAM B. HUGHES, OF CHESTNUT HILL, PENNSYLVANIA.

GAS-PRODUCER.

No. 852,957.

Specification of Letters Patent.

Patented May 7, 1907.

Application filed May 26, 1906. Serial No. 318,875.

To all whom it may concern:

Be it known that I, WILLIAM B. HUGHES, a citizen of the United States, residing at Chestnut Hill, in the county of Philadelphia and State of Pennsylvania, have invented certain Improvements in Gas-Producers, of which the following is a specification.

This invention is a gas producer having a revoluble top, a stationary body, a stationary ash receiver, and, beneath a conical ash hopper depending from the producer body, a revoluble table carrying a blast pipe which extends upwardly into the producer body and a stirring device which revolves beneath the ash hopper, in combination with mechanism for simultaneously revolving the top and the table and feeding the fuel so as to properly distribute it within the body.

The object of the improvements is to provide a simplified, automatically operating producer of high efficiency.

In the accompanying drawings Figure 1 represents a side elevation of a gas producer embodying my improvements, a section being broken away for the purpose of illustration; Fig. 2 represents a vertical sectional view of the structure shown in Fig. 1; Fig. 3 represents a top plan view of the same, and Fig. 4 represents a sectional view taken 30 through the cover and the fuel feeding mechanism.

As shown in the drawings, the improvements comprise the stationary cylindrical body 1, the stationary cylindrical casing 2 connected with the bottom thereof, and the stationary conical ash receiver 3 depending from the casing 2, the bottom of the ash receiver being closed by the valve 4.

The body has the circular top or cover 5, 40 provided with the rim 6 forming a basin and an apron 8 depending into the circular channel 9 on the body to form a water seal. Rollers 10, journaled on the top or cover, run on a track 11 carried by the body, and a rack 12 on the rim is engaged by a pawl 13 pivoted to a short arm 14, the latter being fixed to a shaft 15 journaled on the bracket 16 and fixed to the lever 17. The pawl is operated, to revolve the top of the producer, by means 45 of a connecting rod 18, pivoted to an adjustable shoe 19 on the lever and to an arm 20 fixed to a shaft 21 journaled in a stationary bracket 22.

The basin formed by the top of the producer is supplied with water by the pipe 9' and overflows through the openings 25 and

the passages 26 to the channel 9, which discharges by an opening 27 and a waste pipe 28, whereby circulation is effected.

Placed eccentrically of the top is a duct 29 which discharges by the elongated opening 30 into the producer top and receives coal from the hopper 31. The discharge from the hopper into the duct is controlled by a valve 32 carried by an arm 33 on a spindle 34 longitudinally movable and revoluble in the bearing 35. The spindle is supported by the counter-weighted lever 36 fulcrumed on an arm 37, which is revolably supported by the bearing 38 so that the valve can be lowered and revolved to open the port 38 in the bottom of the hopper.

Coal is fed from the hopper through the passage 30 by the vane wheel 39 fixed on the revoluble shaft 40, the vanes 39' being of increasing depth toward the periphery of the top to effect an increased feed for the more extended area traversed. The shaft 40 has a beveled pinion 41 fixed thereon which engages a beveled pinion 42 fixed to a stationary shaft 43, the hopper having a sheave 44 fixed thereon which revolves on the shaft 43.

The top is provided with poke-holes 45 through nipples 46 which extend above the water level in the basin.

Within the casing 2, beneath the conical hopper 47 which depends from the body 1, is the table 48 with a rim 49 thereon forming a basin like holder for the ashes, the table having the centrally disposed conical portion 50 which carries the blast pipe or passage 51. A spider 52 fixed within the pipe is fixed to a shaft 53 revoluble in a step bearing 54 which is supported by cross beams 54'. A circular rack 55 on the bottom of the table is engaged by a pinion 56 fixed on a shaft 57 which is journaled in the bearings 58 and 59. The shaft is revolved, to revolve the table, by the spur-wheel 24 fixed thereon which is engaged and driven by the pinion 23 fixed on the shaft 21. Carried by a bearing 60 on the table is an adjustable bar 61 which can be set at the desired position for raking or cutting through the ashes between the hopper and the table.

A blower 62, connected to the casing 2 forces air therethrough and by way of the passages of the parts 50 and 51 through the coal in the producer body, the gas escaping by the outlet 63, it being understood that the parts 1, 2 and 3 are connected so as to form an air tight vessel.

It will now be understood that as the top 5 revolves the fuel is fed into the body 1 of the producer through the opening 30 by means of the vane-wheel 39, and the ashes 10 are discharged from the hopper 47 by the revolving table 48 and the bar 61, the body remaining stationary while the top and the table are revolved by means of the mechanism for operating them as previously described. The ashes accumulated in the receiver 3 are withdrawn by way of the valve 4 from time to time, and the combustion is carried on by means of air forced by the blower 62 into the casing 2 whence it is carried through the body of fuel, from which the gas escapes by the outlet 63.

Having described my invention I claim:—

1. A gas producer having a stationary

body, a revolving top, a revoluble ash support beneath said body, and mechanism for connecting and simultaneously revolving said top and support.

2. A gas producer having a stationary body, a revolving top, a revoluble table beneath said body, a blast pipe fixed to and revoluble with said table, a rack fixed to said table, a rack fixed to said top, and mechanisms whereby said racks are engaged to revolve said table and top.

In testimony whereof I have hereunto set my name this 24th day of May, 1906, in the presence of the subscribing witnesses.

WM. B. HUGHES.
